UNITED STATES PATENT OFFICE.

DOLE I. BREECE, OF ALMA, MICHIGAN.

BEET-TOPPER.

1,269,371.

Specification of Letters Patent. Patented June 11, 1918.

Application filed January 27, 1917. Serial No. 144,848.

To all whom it may concern:

Be it known that I, DOLE I. BREECE, a citizen of the United States, residing at Alma, in the county of Gratiot and State 5 of Michigan, have invented certain new and useful Improvements Beet-Toppers; and I do hereby declare the following to be a full, clear, and exact description of the invention, such as will enable others skilled in the art 10 to which it appertains to make and use the same.

This invention relates to a beet topper and the primary object of the invention is to provide a beet topping structure which 15 may be attached to the supporting structure of a sugar beet cultivator, in lieu of the cultivator beams, standards and shovels, which topper structure will top and crown the beets, preparing them for uprooting by any 20 suitable type of uprooting structure.

An object of this invention is to provide a beet topper structure as specified which includes a supporting frame attached to a pair of beams, which beams are adapted for connection to the axle of an ordinary beet cultivator, in the usual manner and to provide a pair of auxiliary supporting frames which are adjustably connected to the main supporting frame for lateral adjustment with 25 respect to each other, which auxiliary supporting frames carry beet crowning knives and guide plates, which guide plates engage the tops of the beets, mash them down and regulate the position of the crowning 30 knife, which crowning knife is adjustably connected to the auxiliary supporting frames.

With the foregoing and other objects in view, this invention consists in such novel 40 features of construction, combination and arrangement of parts as will be hereinafter more fully described, illustrated in the accompanying drawings and claimed.

In describing the invention in detail, reference will be had to the accompanying drawings wherein like characters designate like and corresponding parts throughout the several views, and in which:—

Figure 1 is a side elevation of the improved beet topper.

Fig. 2 is a plan view of the topper.

Fig. 3 is a fragmentary side elevation of the topper illustrating the crowning knife.

Fig. 4 is a longitudinal section through 55 Fig. 3.

Fig. 5 is a section on the line 5—5 of Fig. 3, and

Fig. 6 is a detail perspective of the crowning knife.

Referring more particularly to the drawings, 1 designates the supporting wheels of an ordinary beet cultivator, and 2 the supporting axle thereof. The beet topping structure which is generically indicated by the numeral 3, comprises a rectangular supporting frame 4, which is preferably constructed of angle iron and has its side rails extended forwardly, to form beams 5, which are connected in any suitable manner to the axle 2. The horizontal portions of the ends of the 70 rectangular frame 4 have a plurality of substantially U-shaped members 6 adjustably connected thereto, through the medium of bolts and a plurality of openings 7 which are formed in said horizontal portions. The 75 substantially U-shaped members 6 have their bight portions 8 positioned horizontally, and below the frame 4. The substantially U-shaped members 6 are preferably constructed of angled iron, and they have the 80 upturned edges 9 of a guiding plate or member 10 adjustably connected thereto by means of bolts 11, which extend through slots 12 formed in the upstanding portion of the members 6 so as to permit of a limited 85 vertical adjustable movement of the knife adjusting plate 10 upon its engagement with beet tops of various heights, for regulating the position of the topping and crowning knife 14.

The bolts 11 extend slidably through the slots 12. The crowning or topping knife 14 comprises a horizontal blade 15, which has its longitudinal edges beveled as shown at 16, to form sharpened or knife edges 95 for topping or crowning the beets. The horizontal blade 15 of the knife has a pair of upstanding plates 17 and 18 formed upon its end which plates are provided with vertically positioned slots 19 through which 100 bolts 20 extend. The bolts 20 extend through the vertical portions 9 of the knife adjusting plate 10 and the slots 19 will permit of vertical adjustment of the blade 14 with respect to the knife adjusting plate 10 105 so that the distance between the under surface of the plate 10 and the cutting edges 16 of the knife blade 15 may be regulated as desired.

The plate 10 has its forward end up- 110

2
turned as clearly shown at 21 for engaging and mashing down the tops of beets. A pair of the topping structures including the plate 10 and the crowning or topping knife structures 14 are provided, and they are adjustable laterally with respect to each other, through the medium of the holes 7 formed in the end of the frame 4 so that they may be adjusted to accommodate rows which are 10 at different distances apart.

In the operation of the improved beet topper; the upturned end 21 of the plate 10 will engage the tops of the beets, and mash them downwardly. The tops, bearing 15 against the under surface of the plate 10 will have a tendency to force the plate upwardly, through the medium of its adjustable connection with the bight portions 8 of the U-shaped members 6, and as the 20 knives 14 are rigidly connected to the upstanding sides 9 of the plate 10, the knives will be moved upwardly in unison with the movement of the guiding plate, thereby 25 positioning the cutting edges 16 of the knives in the proper position for cutting the desired amount of the crown off the beets. The lighter the foliage, and the deeper into 30 the ground the crowns of the beets are positioned, the less upward pressure there will be upon the plate 10.

From the foregoing description taken in connection with the accompanying drawings, the advantages of construction and of the method of operation of the improved 35 beet topper will be readily apparent to those skilled in the art to which this invention appertains, and while in the foregoing description, the principle of the operation of this invention has been described together 40 with various features of construction, it is to be understood that certain minor features of construction, combination and arrangement of parts may be altered to suit practical conditions provided such alterations 45 are comprehended within the scope of what is claimed.

What is claimed is:—

1. In a beet topper, the combination of 50 a substantially rectangular supporting frame, the sides of said frame being extended forwardly and adapted for attachment to a wheeled axle, a plurality of substantially U-shaped members arranged in pairs and adjustable laterally of said frame, 55 and a beet topping knife carried by the

lower bight portions of said substantially U-shaped members.

2. In a beet topper, a substantially rectangular supporting frame, the sides of said supporting frame being extended forwardly and adapted for connection with a wheeled axle, a plurality of substantially U-shaped members arranged in pairs and adjustably connected to said rectangular supporting frame for lateral adjustment with respect to each other, a beet crowning knife adjustably carried by each pair of said U-shaped members and comprising a horizontal blade having its longitudinal edges sharpened. 60 65

3. In a beet topper, a substantially rectangular supporting frame, a plurality of U-shaped members arranged in pairs and adjustably connected to said supporting frame for lateral adjustment with respect to each other, a knife adjusting plate adjustably connected to each pair of said U-shaped members and adapted for movement under pressure of beet tops, and a crowning knife connected to each of said knife adjusting plates. 70 75

4. In a beet topper, a substantially rectangular supporting frame, a plurality of U-shaped members arranged in pairs and adjustably connected to said supporting frame for lateral adjustment with respect to each other, a knife adjusting plate adjustably connected to each pair of said U-shaped members and adapted for movement under pressure of beet tops, a crowning knife comprising a horizontal blade having its longitudinal edges sharpened, upstanding plates formed upon the ends of said blades, and means for adjustably connecting said upstanding ends to said knife adjusting plates. 80 85 90 95

5. In a beet topper, a supporting frame, a plurality of depending members carried by said frame and adapted for lateral adjustment, said members arranged in pairs, a knife adjusting plate yieldably connected 100 to each pair of said members for vertical movement, and a topping knife carried by each knife adjusting plate for movement with the plate.

In testimony whereof I affix my signature 105 in presence of two witnesses.

DOLE I. BREECE.
